LAVATORY

Clarence J. Rodman, Alliance, Ohio

Application December 23, 1950, Serial No. 13,561

Term of patent 14 years

(Cl. D4—2)

To all whom it may concern:

Be it known that I, Clarence J. Rodman, a citizen of the United States, residing at Alliance, State of Ohio, have invented a new, original, and ornamental Design for Lavatory, of which the following is a specification, reference being had to the accompanying drawing, forming a part thereof.

Fig. 1 is a perspective view of a lavatory showing my new design;

Fig. 2 is a top plan view; and

Fig. 3 is a sectional view thereof taken on the line 3—3 of Fig. 2.

The two halves of the lavatory are symmetrical about the line 3—3 of Fig. 2.

The dominant feature of my design resides in that portion shown in full lines in the drawing.

I claim:

The ornamental design for a lavatory, as shown and described.

CLARENCE J. RODMAN.
